UNITED STATES PATENT OFFICE.

WALTER GILLESPIE, OF MONTREAL, QUEBEC, CANADA, ASSIGNOR TO
GEORGE A. DRUMMOND, OF SAME PLACE.

FURNACE-GRAVE.

SPECIFICATION forming part of Letters Patent No. 225,590, dated March 16, 1880.

Application filed January 24, 1880.

To all whom it may concern:

Be it known that I, WALTER GILLESPIE, of the city of Montreal, in the District of Montreal, and Province of Quebec, Canada, have 5 invented certain new and useful Improvements in Furnace-Grates; and I do hereby declare that the following is a full, clear, and exact description of the same.

My invention, which is specially applicable 10 to the boilers of marine and stationary engines, has for its objects to keep the fire clean and level, to facilitate stoking, and to evolve the greatest amount of heat from the combustion of a given quantity of coal.

15 It may be described, briefly, as consisting in making the bars of a spiral shape and rotating them continuously half in either direction outward from the center, so as to insure a constant movement of the burning coal toward 20 the bridge.

For full comprehension, however, of my invention, reference must be had to the annexed drawings, forming part of this specification, in which—

25 Figure 1 is a plan view of a furnace-grate embodying my invention, and Fig. 2 a front view of same.

Similar letters of reference indicate like parts.

30 A is the front, and A' the bridge of the furnace or fire-chamber, which may be of any construction found suitable. B B' B' are the bars, of any diameter desired and set any suitable distance apart, and having, as shown in 35 Fig. 1, their whole length which is in contact with the fuel of a spiral form, (the part under the dead-plate being, by preference, straight,) and so arranged that the spirals of one half the bars—*i. e.*, those marked B—shall 40 be opposite to the spirals of the other half, (marked B',) or, in other words, these bars be set right and left.

The ends of the bars are carried through the front of the furnace, and on them are mounted 45 worm-gear wheels C C' C' C', intermeshing with and receiving motion, respectively, from corresponding worm-wheels D D' D', secured on a shaft, E, running the whole length of the furnace or furnaces and rotated from 50 any going part of the engine or machinery by

means of a belt-and-pulley gearing, or in any other way.

The worm-wheels D D' D' are so arranged as to turn the worm-gears C C' C', and with them the bars B B' B', respectively, in opposite directions, each set turning away from the center, as shown in Fig. 2. 55

The shaft E, with its worm-wheels, and the worm-gears C' C' C' C' are suitably inclosed.

The bars are, by preference, made hollow, 60 and any suitable means may be used for passing water through them, such, for instance, as a continuous feed-pipe with branches to each bar, the bridge in such a case being hollow and provided with any suitable discharge; 65 and all parts of the furnace other than the bars and the features just described form no part of the invention and can be built in any way.

The operation of my invention will be so 70 clearly understood from the foregoing and the drawings that it is only necessary to say that the continuous rotation of the shaft at the rate of speed desired will turn the bars half in each direction outwardly from the longitudinal axis of the furnace, and that this double movement of the spirally-shaped bars will carry the fuel from the center of the front of 75 the furnace, where it is put in gradually and continuously backward to the bridge, at the same time spreading it out on either side.

By this means I obtain an even fire, which can be easily stoked, as it will hardly require raking, and the constant revolution of the bars entirely obviates any choking or difficulty 85 from clinkers. In addition to this a very large proportion of the gases is consumed and utilized, and a corresponding amount of heat evolved.

Although, as before mentioned, my invention is specially adapted to the boilers of marine and stationary engines, it may be used for all classes of furnaces for raising steam, and supplementary mechanism be provided for rotating the continuous shaft where the 90 means do not exist or are not applicable.

I am aware that revolving bars have previously been used, and therefore do not claim such broadly.

What I claim is as follows:

1. In a furnace-grate, spiral bars revolving in opposite directions outward from the longitudinal axis of the furnace, substantially as set forth, and for the purposes described.
- 5 2. The furnace-bars B B' B'', revolving in opposite directions, and carrying on their ends worm-gears intermeshing with and rotated by

worm-wheels mounted on a continuous revolving shaft, all substantially as herein shown and described.

WALTER GILLESPIE.
